A. J. Davies

UNITED STATES PATENT OFFICE

2,098,419

MOTOR VEHICLE HOIST

Joseph Done Handley, Liverpool, England

Application June 22, 1936, Serial No. 86,572
In Great Britain December 11, 1935

3 Claims.

(Cl. 240—2)

This invention relates to vehicle hoists or lifts of the type employed in garages and service stations for raising motor vehicles off the ground to facilitate their inspection, servicing and repair. Such hoists or lifts usually comprise a structure embodying a pair of runway platforms on to which the vehicle to be raised is run; and the hoist is elevated as by power-driven screw mechanism, or more commonly by a central hydraulic 10 ram operated from an air-pressure plant.

According to the present invention there is incorporated with the vehicle hoist or lift a system of electric lighting serving to illuminate the vehicle on the hoist. The lighting fitments are attached to or built into the hoist, and constitute a permanent attachment or installation thereof.

The hoist lighting system is intended primarily for illuminating the underside of the vehicle on the hoist. For this purpose a series of electric 20 lamps may be fitted to the usual runway platforms of the hydraulic or other type of hoist, the lamps being disposed along the insides of the platforms, so that the light therefrom is directed upwards on to the underside of the vehicle. Additional lamps may also be fitted to the cross 25 girder or other structure supporting the platforms. By thus employing a comparatively large number of lamps a strong and uniform lighting over the whole of the vehicle base area can be obtained.

In one embodiment of the invention the wiring for the lamps is housed in conduits run under the platforms and across the support girders; and it is led to a pair of plug-in sockets disposed at opposite ends of the hoist, by means of one or other of which the hoist lighting system may be connected to the ordinary mains supply through a cable to a wall plug or connector. The individual lamps are carried by swivelling brackets fixed 35 to the underside of the platforms, the brackets enabling the lamps to be turned outwards from beneath the platforms into position for throwing a light upwards under the vehicle on the hoist.

The conduit and bracket fitments of the electrical system may be readily incorporated in an existing hoist.

The invention is illustrated by way of example in the accompanying drawing, in which:—

Fig. 1 is a somewhat diagrammatic plan view 50 of a hydraulic type of motor vehicle hoist incorporating an electric lighting system;

Fig. 2 is an enlarged end view of Fig. 1;

Fig. 3 is a side view of a swivelling lamp bracket.

The hoist shown in the drawing is provided 55 with the usual pair of side runway platforms 1, on

to which the motor vehicle to be raised is run, and along the inside edges of the platforms are disposed integral upstanding flanges 2 for transversely locating the vehicle on the hoist. The platforms are carried by a cross-girder structure 3 mounted centrally at the head of a hydraulic ram 4 which may be operated from an air-pressure plant.

Disposed under and near the insides of the platforms, and also on the support structure 3, 10 is a series of swivelling lamp brackets 5, by means of which the lamps 10 may be swung out from a protected position under the platforms in order to throw a light upwards and so illuminate the underside of the vehicle on the hoist. The brackets consist of a tubular elbow piece 6, at one end threaded and socketed on to the stem 7 of a T-shaped conduit connector, on which the bracket is adapted to swivel and to which it is frictionally gripped by a spring 16; while at the other end of 20 the elbow piece 6 is formed an annular cup 9, on which is fitted a holder for an electric lamp 10. In order to protect the lamp against breakage, and also against the deposit of oil, which would otherwise be liable to form a hard oil-baked film owing to the heat of the lamp bulb, the lamp is enclosed within a glass sleeve 11 fitting at one end into the bracket cup 9 and closed at its outer end by a cup-shaped cap 12. The cup 9 and cap 12 are formed with lugs 13 receiving 30 the ends of a pair of tie rods 14, the outer and projecting ends of which are threaded to receive retaining nuts 23. The ends of the glass sleeve 11 are preferably butted against rubber or fibre ring washers 15 in the cups 9 and 12.

The wiring for the lamps, which are connected in parallel and may be of relatively low wattage, is enclosed in conduits 18 run along the underside of the platforms 1 close to the inside flanges 2, the T connectors 8 carrying the lamp brackets 40 5 being positioned on the hoist as indicated in Fig. 1, four on each platform and two on opposite sides of the girder structure 3. As shown in Figs. 2 and 3, the brackets 5 are pivoted for movement about a vertical axis, so that they may be 45 turned outwards clear of the platforms and thereby allow the light from the lamps 10 to be thrown upwards under the vehicle.

One or more lamps may also if desired be fitted to fixed or hinged extension arms in order 50 to direct light under the centre of the vehicle.

The wiring system 17 for the lamps 10 is run to a pair of plug-in sockets 19 fitted under the platforms at opposite ends of the hoist, by means of one or other of which the lighting system may 55

be connected through a cable 20 to a wall switch or connector 21 in circuit with the ordinary mains supply, or with a low-voltage source. The provision of the two connectors 19 enables the 5 mains supply being tapped from both ends of the hoist, which is of advantage when the hoist is rotated, in that only a short cable 20 is then necessary.

The arrangement just described is particularly 10 suitable for fitment to an existing hoist.

The ordinary method of illuminating the underside of a motor vehicle on a garage hoist or lift is by means of a hand inspection lamp fitted to an extension cable connected to the mains 15 supply. This has many disadvantages; the lamp gives only a localized light; the operator has to carry the lamp about with him, and hold or position it at the place where he is working; rough handling leads to frequent bulb breakages; and 20 a long length of cable is necessary, which is liable to become entangled or broken, and which through being dragged over the ground becomes dirty and oil-soaked, impairing the insulation.

These disadvantages are obviated by incorporating 25 an electric lighting system as a permanent installation of the hoist. A strong and uniform light is provided over a large area, and the operator has both hands free for working. Except for the short cable 20, which is held up well clear 30 of the ground, there is no loose wiring or cable, and consequently the movements of the operator or other persons are unrestricted. In addition, the conduit casing 18 completely protects the cables 17, and if the wiring should become broken 35 or the insulation defective, the system will be earthed through the conduits and the hoist structure, so preventing the possibility of shocks.

Although the invention has been described with 40 reference to a hydraulic type of hoist, it is not limited to this application, and may be incorporated in the several other types of hoists or lifts employed in garages and service stations for facilitating the inspection, servicing and repair of motor vehicles.

45 I claim:—

1. A motor vehicle hoist of the type referred

to, wheel platforms thereon on to which the vehicle to be raised is run, a series of electric lamps fitted to the platforms and serving to illuminate the underside of the vehicle on the hoist, said lamps being carried by brackets fixed on the 5 underside of the platforms, the brackets being mounted for swivelling movement to enable their being turned from a protected position under the platforms into a position for illuminating the underside of the vehicle, a wiring system connecting 10 said series of lamps to a connector element on the hoist, said wiring system being housed in conduits fixedly secured to the platforms, and a source of electric current supply tapped from the connector on the hoist, said 15 series of lamps and wiring system comprising a permanent installation of the hoist.

2. A motor vehicle hoist of the type referred to, wheel platforms thereon on to which the vehicle to be raised is run, a series of electric lamps 20 fitted to the platforms and serving to illuminate the vehicle on the hoist, said lamps being carried by brackets fixed on the underside of the platforms, the brackets being mounted for swivelling movement about a vertical axis to enable their 25 being turned from a protected position under the platforms into a position for illuminating the underside of the vehicle, each such bracket comprising an elbow-piece at one end socketed for swivelling movement on a vertical spigot and at 30 its other end provided with a lamp socket, a wiring system connecting said series of lamps to a connector on the hoist, said series of lamps and said wiring system comprising a permanent installation of the hoist, conduits fixedly secured 35 on the hoist and housing said wiring, a series of T-shaped connections for the said conduits, on to the stems of which the lamp brackets are spigotted, and a source of electric current supply.

3. In a motor vehicle hoist according to claim 2, 40 a swivelling bracket the free end of which terminates in an annular cup fitted with an electric lamp socket and receiving a glass shield for the lamp.

JOSEPH DONE HANDLEY. 45
